UNITED STATES PATENT OFFICE.

KIRK D. HOLLAND, OF FORT WORTH, TEXAS.

APPARATUS FOR DEMONSTRATING AND TESTING PISTON PACKING-RINGS.

1,241,849.

Specification of Letters Patent. Patented Oct. 2, 1917.

Application filed June 24, 1916. Serial No. 105,775.

To all whom it may concern:

Be it known that I, KIRK D. HOLLAND, a citizen of the United States, residing at Fort Worth, in the county of Tarrant and State of Texas, have invented certain new and useful Improvements in Apparatus for Demonstrating and Testing Piston Packing-Rings, of which the following is a specification.

10 My invention relates to a method and apparatus for testing and demonstrating packing rings; and the object is to provide a simple apparatus by which packing rings can be conclusively tested and by which the 15 operation or function of packing rings can be quickly and clearly demonstrated and to provide a method of demonstrating the practicability of packing rings. Other objects and advantages will be fully explained 20 in the following description and the invention will be more particularly pointed out in the claims.

Reference is had to the accompanying drawings which form a part of this application.

Figure 1 is a vertical section of a cylinder, showing a piston therein. Fig. 2 is a vertical section of a cylinder without a piston, the latter having the interior uniform 30 from end to end and the cylinder shown in Fig. 1 being smaller at the open end. Fig. 3 is a vertical section of two cylinders formed of a single casting. Fig. 4 is a plan view of the cylinder shown in Fig. 3. Fig. 35 5 shows a side elevation of cylinder with a vertical slot therein.

Similar characters of reference are used to indicate the same parts throughout the several views.

40 This invention includes a cylinder 1 having a bottom 2 screwed into the cylinder and provided with a pet cock or air cock 3. The cylinder 1 is tapered on the interior so that the interior of cylinder 1 is smaller near the 45 open end than it is at some distance from the open end. The part 4 is smaller than the part 3, the enlargement being between the dotted lines 5 and 6. The open end of the cylinder 1 is beveled at 7 for convenience 50 in inserting the piston. A piston 8 is shown in the cylinder with packing rings 9.

The cylinder 10, shown in Fig. 2, is of uniform size throughout its length. This has an interior like a cylinder which has not 55 been worn. The bottom 11 may be screwed in the cylinder up to the shoulder 12. This

cylinder is provided with a cock 3 and is beveled at 13 for convenience in inserting a piston.

If preferable, the two cylinders can be 60 made of a single piece of metal, as shown in Figs. 3 and 4. The cylinder 14 has the same interior construction as the cylinder shown in Fig. 1. The cylinder 15 has the same interior construction as the cylinder shown in 65 Fig. 2.

The tapering of the interior of cylinder 1 may be at different locations from that shown in Fig. 1 and the bottom of the cylinder may be formed integral with the cylinder. Air may be admitted to the cylinder 70 below the pistons in any suitable manner.

The purpose of the tapering of the interior of the cylinder is to illustrate the shape to which cylinders are worn in service and 75 also to illustrate or demonstrate how expansion packing rings will expand and follow the wall of the cylinder during service.

The packing rings will be compressed and remain compressed until they pass the 80 smaller part of the interior of the cylinder. See rings 16 and 17 in Fig. 5. They are passing through the smaller part of the interior. See the same rings at position 18 in the same Fig. 5. The rings at their open 85 points have spread apart. As the piston presses the rings down, the rings will expand and press out against the larger part of the cylinder as soon as pressed down to the larger part and no opening between the 90 rings and the cylinder will be left. The cylinder in Fig. 5 has a vertical slot 19 so that the condition of the rings can be observed at different points. Various changes in the sizes and proportions and construction of 95 the different parts may be made without departing from my invention.

For illustrating the efficiency of the packing rings, press a piston with packing rings fitted thereon down in the cylinder. If the 100 piston goes down easily, this means that air escapes and that the rings are deficient. If it is difficult to press the piston down, this means that the rings do not let the air pass and that the rings are competent packing 105 rings and efficient. When the pistons are to be removed from the cylinders, air may be let in the cylinder below the pistons. The devices shown give an accurate test of the efficiency of the rings and the devices may 110 be used in demonstrating the rings to prospective purchasers.

What I claim, is,—

1. Packing ring testing and demonstrating apparatus comprising an open end cylinder, a piston having grooves therein to receive packing rings to be forced into the said cylinder after packing rings are fitted thereon, a handle for operating said piston, and means for introducing air into the cylinder between the end of the piston and the closed end of the cylinder.

2. Packing ring testing and demonstrating apparatus comprising a cylinder open at one end and closed at the other end and

having a smaller bore near the open end of the cylinder than the bore of the greater portion of the interior, a piston having grooves therein to receive packing rings and adapted to be forced into said cylinder after the packing rings are fitted thereon, and means for letting air into the cylinder between the end of the piston and the closed end of the cylinder.

In testimony whereof, I set my hand this 10th day of June, 1916.

KIRK D. HOLLAND,
